UNITED STATES PATENT OFFICE.

ULRICH HAGMANN, OF ST. GEORGE, NEW YORK, ASSIGNOR TO THE QUAKER OATS COMPANY, OF CHICAGO, ILLINOIS, A CORPORATION OF NEW JERSEY.

DESIGN FOR A CUP OR SIMILAR ARTICLE.

Application filed April 20, 1927. Serial No. 21,652. Term of patent 3½ years.

To all whom it may concern:

Be it known that I, ULRICH HAGMANN, a citizen of Switzerland, and resident of St. George, in the borough and county of Richmond, city and State of New York, have invented a new, original, and ornamental Design for a Cup or Similar Article, of which the following is a specification, reference being had to the accompanying drawing, forming part thereof, in which—

Fig. 1 is a front elevation, partly broken away to show the inner ornamentation, of a cup or similar article, illustrating my new design and Fig. 2 is a plan view of the cup shown in Fig. 1.

I claim:

The ornamental design for a cup or similar article, as shown and described.

ULRICH HAGMANN.
